UNITED STATES PATENT OFFICE.

GERARDO MARSICO, OF NEW YORK, N. Y.

MECHANICAL HORN.

1,168,090.

Specification of Letters Patent. Patented Jan. 11, 1916.

Application filed March 2, 1914. Serial No. 821,894.

To all whom it may concern:

Be it known that I, GERARDO MARSICO, a subject of the King of Italy, residing at the borough of Manhattan, city, county, and State of New York, have invented certain new and useful Improvements in Mechanical Horns, of which the following is a specification, reference being had therein to the accompanying drawings, which form a part thereof.

My invention relates to mechanical horns and more particularly to a type of diaphragm horns wherein the displacement of the diaphragm is effected by means of an electromagnet. Heretofore horns of this type have been extensively made and used, but they have not proven entirely satisfactory because it has been found impossible to secure a structure wherein the displacement of the diaphragm has been sufficiently great, or its vibrations sufficiently rapid to develop a signal of the desired intensity or amplitude. Furthermore, after a diaphragm has been set in motion, it develops a movement independent of the power being applied thereto, and a failure of the actuating means to come to stop with the diaphragm, results in interference with the flexure of the diaphragm, with a resultant discordance of, and loss of intensity in, the sound developed by the diaphragm. In horns, of the electromagnetic type, or "buzzer" horns, there is a loss of efficiency due to the absence of a sufficiently forceful impact of the striker member with the diaphragm contact piece, and a gradual loss of efficiency with a continued use of the horn.

By my invention, I aim to provide a mechanical horn structure wherein the diaphragm is displaced by means of an electromagnet, in which the emitted signal will come to pitch substantially instantly with the closing of the circuit to the magnet and the displacement of the diaphragm will be of sufficient magnitude to insure a loud, quick, sharp warning signal. In such a structure a sustained signal of substantially uniform intensity may be sounded, the actuating means moving synchronously with the diaphragm and avoiding interference with the flexures of reflexes thereof. To secure economy in the operation of the horn

in addition to the desired displacement of the diaphragm and the avoidance of interference with the free vibrations thereof, I so construct, my improved horn that a blow of the desired force may be delivered to the diaphragm through a weighted armature controlled by a single electro-magnet.

I also provide adjustable means arranged externally of the horn casing, whereby the make and break mechanism may be adjusted in a manner to time the striker member to the diaphragm, and regulate the force of the blow transmitted to the diaphragm so as to attune the horn, secure the desired degree of displacement of the diaphragm and bring the movement of the striker member into synchronism with the flexures of the diaphragm. This adjustment means may also be used to take up wear, or compensate for any loss of efficiency arising from the continued use of the horn.

I also construct my electro-magnet and so combine it with the coöperating elements of the horn, as to insure a magnetic field of great intensity and utilize the entire force of the blow delivered by the striker member in displacing the diaphragm. I also provide means whereby the normal relation of the diaphragm contact member and the striker member may be regulated to aid in attuning the horn.

Further, and minor, characteristics of my invention are the assembling of the actuating mechanism in a unitary structure which may be quickly and accurately assembled in the horn, and the detailed construction of the various parts of the structure for insulating the make and break mechanism and securing the desired rigidity of the various parts.

The invention consists in the novel features of construction and combination of parts hereinafter set forth and described and more particularly pointed out in the claims hereto appended.

Referring to the drawings: Figure 1 is a perspective view of a mechanical horn embodying my invention; Fig. 2 is a longitudinal vertical section through the rear casting, and Fig. 3 is a section of the main actuating mechanism on the line 3-3 of Fig. 2, the diaphragm contact member being shown.

Like letters refer to like parts throughout the several views.

In the form of the invention shown in the drawings, *a* indicates an ordinary amplifier carried by the casing *b* and communicating with the sound outlet opening *b'* thereof. The diaphragm *c*, which may be of any desired material capable of withstanding the stress thereon, is mounted within said casing *b* between said sound outlet opening and the cup, or rear casing *d*. The dimensions and design of these parts are immaterial to my invention, so long as a clear field within which the diaphragm may vibrate is afforded.

15 The actuating mechanism is mounted within the cup or casing *d*, being firmly secured with relation to said cup or casing and the diaphragm. This mechanism comprises an electromagnet *e* mounted upon the angular plate *f* carrying the screw bolts *f'-f'* by means of which the said mechanism is secured in place. The cup or casing *d* being cylindrical, I make said plate narrow and mount the nuts *f²* *f²* upon the bolts *f'-f'* to facilitate the assembling of the actuating mechanism independently of the remainder of the horn. The plate is clamped firmly in place by the nuts *f³* *f³* coöperating with the bolts *f'-f'* externally of the cup or casing *d*.

30 Mounted upon the plate *f* by means of the angular spring strip *g* is a weighted armature *h* positioned adjacent one end of the magnetic core of the electro-magnet *e*. One angle of the strip *g* rests upon the plate *f*, being insulated therefrom by the sheet *g'* of insulating material. The strip *g* is held upon the plate *f* by the bolts *f'-f'*, suitable washers being interposed between the bolt heads and the strip *g*.

35 The make and break mechanism comprises the spring tongue *g²* carried by the movable part of the spring strip *g*, and the opposed contact *g³* mounted in one arm of the plate *f*. The said contact *g³* may be and preferably is provided with the usual platinum tip. One terminal *i* of the leads of the battery or other source of electrical supply, is connected directly with one terminal of the 50 coil, while the other *i'* is connected with the plate *f*. The other terminal of the coil is connected with the strip *g*.

To develop a magnetic field of the desired intensity, I wind the coil of the magnet *e* upon a spool of insulating material, which spool has a large bore. Mounted in said bore is a cylindrical core *k*, also having a large bore, which core is of soft iron or other magnetic material. The ends of said core 55 project beyond the heads of the spool *j*, that end adjacent the armature *h* being flanged at *k'* to present a substantial area to said armature. The other end of the core is firmly secured, as by means of screw threads, to the 60 forward angle of the plate *f*. If desired,

means as the screw *k²* may be used for locking said magnet with relation to the bracket or frame *f*.

65 The diaphragm *c* is provided with an elongated contact *m* firmly connected therewith by means of the anvil *c'*. Said contact is of materially smaller diameter than the bore of the core *k* and extends longitudinally therethrough, projecting slightly beyond the end thereof adjacent the armature *h*. This projecting end is normally spaced 70 slightly away from said armature for the two-fold object of giving the armature a slight lead before placing it under a load and permitting that reflex action of the diaphragm incidental to the operation of the horn. This spacing of the contact from the armature also aids in preventing interference with the flexure of the diaphragm by the armature. To permit accuracy in the 75 spacing of this contact *m* with relation to the armature, it is adjustably mounted with relation to the anvil *c'* by means of co-operating screw threads, the lock nut *c²* being provided to hold it in any adjusted position.

80 To facilitate the timing of the actuations of the armature with relation to the vibrations of the diaphragm and to permit the adjustment of the horn and prevent interference of the armature with the vibrations of the diaphragm, I provide the contact *g³* with an elongated screw threaded stem *g⁴* the head of which projects through the casing *d* and is adapted to be set in any adjusted position by means of the lock nut *g⁵*. This screw threaded stem is movable in screw threads in one arm of the bracket or plate *f*.

85 The operation of the herein described device is substantially as follows: When it is desired to actuate the horn, the circuit is closed by means of an ordinary push-button not shown. The circuit would be from the terminal *i'* to the plate *f*, therethrough to the contact *g³*, to the spring plate *g*, and therefrom through the core, to the terminal *i*, thus energizing the core *k*. This core being hollow and of large diameter, will exert a powerful influence upon the armature *h*, the attractive force being augmented by the enlarged flange *k'*. Not only will this flange 100 act upon the armature *h* but the exposed interior portion of the core will also act thereon.

105 The contact *m*, being of small diameter, moves freely through the core *k* and being spaced away therefrom is not retarded by the magnetism in said core nor by frictional engagement therewith. I have been unable 110 to determine whether or not the magnetic circuit acting upon the contact *m* materially aids the armature *h* in imparting movement to said contact or aids in synchronizing the 115 movements of the diaphragm with those of 120

the armature. Theoretically, there would be a tendency of the magnet e to act as a solenoid with relation to said contact m , and I believe that the passing of the contact m through the hollow core aids materially in securing the desired degree of displacement of the diaphragm and in avoiding interference in the free vibration thereof.

The slight lead given to the armature h before its engagement with the contact m accentuates the initial power the blow imparted to the diaphragm through said contact, while at the same time permits the diaphragm upon its reflex action, to pass beyond its normal plane without interference from the armature.

In assembling the device the various parts carried by the plate f are assembled in relation thereto with exception of the contact g^2 and these parts are all assembled in the horn at one and the same time.

After the horn has been assembled, the electrical contact g^2 may be adjusted while the circuit is closed, thus bringing the movement of the armature h into synchronism with those of the diaphragms. I have found that by spacing this contact too far from the tongue g^2 , or too near to it, there is interference with the diaphragm due to retardation of the armature; but that at one point of the adjustment of the contact, the diaphragm flexes freely in both directions, and a clear sharp signal is produced, and one of great intensity and amplitude. If there should be a loss of this adjustment, the contact may be readily readjusted.

The intensity of the magnetic field is sufficiently great to bring the horn to pitch substantially instantaneously with the closing of the circuit, and the horn may be readily adjusted so that the signal may be sustained indefinitely without developing conditions leading to interference between the diaphragm and its actuating mechanism.

By mounting the contact m upon an anvil e' as described, I not only am enabled to adjust the contact m with relation to the armature but avoid any tendency toward the "cupping" of the diaphragm.

It is not my intention to limit the invention to the precise details of construction shown in the drawings, it being apparent that such may be varied without departing from the spirit and scope of the invention.

Having described the invention, what I claim as new and desire to have protected by Letters Patent is:-

1. A mechanical horn, embodying a casing having a sound outlet opening, an amplifier communicating with said opening, a rear casing, a flexible diaphragm between said casings, an angular frame plate mounted in and detachable from the rear casing; and diaphragm-actuating mechanism comprising an electro-magnet having a tubular core of

magnetic material fastened at one extremity to one arm of said frame plate, an armature, a resilient support for said armature attached to but insulated from said frame plate, make and break mechanism carried by said armature support, fastening means detachably securing said frame plate within the rear casing, a contact screw having a threaded and adjustable connection with said frame plate and projecting through the rear casing for exterior adjustment, and an elongated contact attached to the diaphragm, projecting through the magnet core and terminating near the armature.

2. A mechanical horn, embodying a casing having a sound outlet opening, an amplifier communicating with said opening, a rear casing, a flexible diaphragm between said casings, an angular frame plate mounted in and detachable from the rear casing; and diaphragm-actuating mechanism comprising an electro-magnet having a tubular core of magnetic material fastened at one extremity to one arm of said frame plate, an armature, a resilient support for said armature attached to but insulated from said frame plate, make and break mechanism carried by said armature support, fastening means detachably securing said frame plate within the rear casing, a contact screw having a threaded and adjustable connection with said frame plate and projecting through the rear casing for exterior adjustment, and an elongated contact attached to the diaphragm, projecting through the magnet core and terminating near the armature, the means for fastening the frame plate to the rear casing serving also as means for fastening the armature support to the frame plate.

3. A mechanical horn embodying therein a casing having a sound outlet opening, an amplifier communicating with said opening, a back casing or cup, a flexible diaphragm mounted in said casing, an actuating mechanism for said diaphragm comprising an angular plate, an electro-magnet having a core of magnetic material having a large bore longitudinally therethrough, one end of said core being secured to one arm of said plate and the other end having a flange beyond the spool of said magnet, an angular spring strip, bolts securing one arm thereof to, but insulated from, said plate, a weighted armature carried by the other arm of said strip adjacent said flange, and a make and break mechanism consisting of a spring tongue carried by said armature support, and a contact screw adjustably mounted in said plate and projecting beyond said rear casing or cup, means co-operating with said bolts whereby said actuating mechanism is mounted within said rear casing or cup, and an elongated contact supported by and having movement with said diaphragm.

and projecting through and beyond said core and terminating near said armature, said contact being of relatively small thickness as compared with the bore of said core, 5 whereby clearance is afforded about said contact within said core.

In witness whereof I have hereunto affixed

my signature, in the presence of two sub-
scribing witnesses, this 27th day of Feb-
ruary, 1914.

GERARDO MARSICO.
